CLAIM

The ornamental design for a biochemical analyzer, as shown and described.

DESCRIPTION

FIG. 1 is a perspective view from front side of a biochemical analyzer showing our new design;

FIG. 2 is a front view thereof; and,

FIG. 3 is a top plan view thereof.

In the drawings, the equal-length broken lines depict unclaimed portions of the biochemical analyzer that form no part of the claimed design. The dash-dot-dash broken lines define the boundaries of the claim. All broken lines form no part of the claimed design.
